(57) **ABSTRACT**

A bollard including a series of at least two nested, inverted U-shaped forms of decreasing height set around a common vertical axis. Each form has an upper transverse portion and two parallel, vertical legs extending therefrom. The U-shaped forms are made of metal pipes, and have physical characteristics such that on impact by a moving vehicle, including an automobile or a truck, the U-shaped forms will initiate a “crumple zone” type reaction, so as to meet governmental standards addressing the threats posed by vehicular traffic.

BOLLARD AND ACCESSORIES FOR USE THEREWITH**CROSS-REFERENCE TO RELATED APPLICATIONS**

The present patent application is a continuation of application Ser. No. 10/252,538, filed Sep. 24, 2002, now U.S. Pat. No. 7,232,275 which is a continuation-in-part of application Ser. No. 29/165,862, filed Aug. 20, 2002, now U.S. Pat. No. Des. 474,846 both of which are incorporated herein by reference in their entireties.

BACKGROUND OF THE INVENTION**1. Field of the Invention**

The present invention relates to public-space fixtures. More specifically, the invention relates to a universal public-space fixture that is adaptable to use as a bollard, usable alone or in a system of bollards, and/or with accessories including but not limited to seating, shelters, signage, lamps, ash-urns, and litter receptacles.

2. Related Art

As a result of the newly defined threat to people occupying ordinary public places in their daily activities, it has now become apparent that conventional public-space fixtures (for example, benches and chairs, litter receptacles, lamps, etc.) must evolve into devices that enhance security, provide conventional function (for example, seating, litter control, lighting, etc.) and allow for the subtle directing of pedestrian traffic. They also must allow for a pleasing, cohesive design system that integrates multiple functions.

Such devices must also eventually meet standards now being written to accommodate the threats posed by vehicular traffic in or near pedestrian spaces. They must likewise provide reasonable barrier protection to entrances, plazas, city streets, areas of congestion, etc. They must simultaneously be cost effective and flexible in design to provide multiple functions. Their design must be easily modified to provide increased strength and protection without inordinately higher cost or significantly larger size, as larger size can easily overwhelm public spaces, making the function of providing protection a deterrent to the successful use of public spaces. Scale is important given the limited space available, the footprint of such devices, and the necessity for the safe movement of pedestrians.

In addition, as a standard requirement, public-space fixtures must be sufficiently attractive to provide permanent and otherwise successful replacement for the concrete slabs and "Jersey Walls" that have been placed temporarily to provide safety.

The same design fixture must be adaptable to seating, shelters, bollards, signage, lamps, and the holding of such elements as ash-urns and litter receptacles. In all such configurations, the fixture must be easily installable as an in-ground or above-ground (bolted-down) structure. The fixture must be configurable to accommodate the evolving standards for the spacing of bollards and barriers, while meeting conventional requirements of accessibility for all people.

These diverse and constantly changing criteria make it necessary to design the elements of public fixtures as part of a set of safety, protective, informational, and convenience requirements.

It is to the solution of these and other problems that the present invention is directed.

2

SUMMARY OF THE INVENTION

It is accordingly a primary object of the present invention to provide a bollard that is cost effective and flexible in design to provide multiple functions.

It is another object of the present invention to provide a bollard that can be easily modified to provide increased strength and protection without inordinately higher cost or significantly larger size.

It is still another object of the present invention to provide a bollard that is adaptable to be used with seating, shelters, signage, lighting, and the holding of such elements as ash-urns and litter receptacles.

It is still another object of the present invention to provide a bollard that is usable alone or in a grouping of other bollards, or with accessories including but not limited to seating, shelters, signage, lighting, ash-urns, and litter receptacles.

These and other objects of the invention are achieved by the provision of a bollard comprising a series of at least two nested, inverted substantially U-shaped forms of decreasing height set around a common vertical axis. "Nested," as used herein, refers to a set of objects of graduated size that can be stacked together, each fitting within the one immediately larger. Each substantially U-shaped form has an upper transverse portion and two parallel, vertical legs extending from the upper transverse portion. The upper transverse portion can be curved, either symmetrically or asymmetrically, with a smooth transition to the legs, or it can be linear and joined to the legs at a miter joint.

In one aspect of the invention, the fixture further comprises means for joining the substantially U-shaped forms together as a unit, for example, at least one center joining plate located below the upper transverse portions of the forms, the forms being fastened to the at least one center joining plate. The at least one center joining plate is substantially perpendicular to the forms, and can comprise a disc having notches at the perimeter thereof for engaging the substantially U-shaped forms, or a spider having radiating arms that engage the substantially U-shaped forms.

In another aspect of the invention, the forms are substantially vertical and the at least one center joining plate is substantially horizontal.

In another aspect of the invention, the fixture further comprises means for anchoring the forms to a support surface, for example, an anchor plate attached to the forms at or adjacent their bottom.

In still another aspect of the invention, the fixture can be used in a public-space system comprising at least one other bollard and/or at least one site amenity (for example, seating, lighting, signage, a shelter, a trash can receptacle, and an ash urn). Where the public-space system includes at least one site amenity, the site amenity is associated with the bollard, for example by being attached thereto.

Other objects, features and advantages of the present invention will be apparent to those skilled in the art upon a reading of this specification including the accompanying drawings.

BRIEF DESCRIPTION OF THE DRAWINGS

The invention is better understood by reading the following Detailed Description of the Preferred Embodiments with reference to the accompanying drawing figures, in which like reference numerals refer to like elements throughout, and in which:

FIGS. 1A and 1B are respectively perspective and top plan views of a first embodiment of a bollard in accordance with the present invention.

FIGS. 2A and 2B are respectively perspective and top plan views of a second embodiment of a bollard in accordance with the present invention.

FIG. 3A is a perspective view of a third embodiment of a bollard in accordance with the present invention.

FIG. 3B is a perspective view of a fourth embodiment of a bollard in accordance with the present invention.

FIG. 4A is a perspective view of the joining plate of the bollard of FIG. 3B.

FIG. 4B is a perspective view of a first alternative embodiment of a joining plate.

FIG. 4C is a perspective view of a second alternative embodiment of a joining plate.

FIG. 5 is a top plan view of an anchor plate of the bollard of FIG. 3.

FIG. 6 is a side elevational view of a universal public-space figure anchored in a concrete footing.

FIGS. 7A, 7B, and 7C are respectively perspective, side elevational, and top plan views of a grouping of bollards in accordance with the present invention.

FIGS. 8A, 8B, and 8C are respectively perspective, side elevational, and top plan views of a first embodiment of a single bollard having seating associated therewith.

FIGS. 9A, 9B, and 9C are respectively perspective, side elevational, and top plan views of a second embodiment of a single bollard having seating associated therewith.

FIGS. 10A, 10B, and 10C are respectively perspective, side elevational, and top plan views of a third embodiment of a single bollard having seating associated therewith.

FIGS. 11A, 11B, 11C, and 11D are respectively perspective, front elevational, side elevational, and top plan views of a first embodiment of a grouping of bollards having seating associated therewith.

FIGS. 12A, 12B, 12C, and 12D are respectively perspective, front elevational, side elevational, and top plan views of a second embodiment of a grouping of bollards having seating associated therewith.

FIGS. 13A, 13B, 13C, and 13D are respectively perspective, front elevational, side elevational, and top plan views of a third embodiment of a grouping of bollards having seating associated therewith.

FIGS. 14A, 14B, 14C, and 14D are respectively perspective, front elevational, side elevational, and top plan views of a fourth embodiment of a grouping of bollards having seating associated therewith.

FIGS. 15A, 15B, 15C, and 15D are respectively perspective, front elevational, side elevational, and top plan views of a fifth embodiment of a grouping of bollards having seating associated therewith.

FIGS. 16A, 16B, 16C, and 16D are respectively perspective, front elevational, side elevational, and top plan views of a sixth embodiment of a grouping of bollards having seating associated therewith.

FIGS. 17A, 17B, 17C, and 17D are respectively perspective, front elevational, side elevational, and top plan views showing a seventh embodiment of a grouping of bollards having seating associated therewith.

FIGS. 18A, 18B, and 18C are respectively perspective, front elevational, and side elevational views of a first embodiment of a grouping of bollards having a shelter associated therewith.

FIGS. 19A, 19B, and 19C are respectively perspective, front elevational, and side elevational views of a second embodiment of a grouping of bollards having a shelter associated therewith.

FIGS. 20A and 20B are respectively perspective and side elevational views of a grouping of a third embodiment of a grouping of bollards having a shelter associated therewith.

FIGS. 21A and 21B are respectively perspective and side elevational views of a bollard having a lamp associated therewith.

FIGS. 22A, 22B, and 22C are respectively perspective, front elevational, and side elevational views of a first embodiment of a bollard having a matching ash urn and trash can receptacle associated therewith.

FIGS. 23A, 23B, 23C, and 23D are respectively perspective, front elevational, side elevational, and top plan views of a second embodiment of a bollard having a matching ash urn and trash can receptacle associated therewith.

FIGS. 24A and 24B are respectively perspective and side elevational views of a first embodiment of a bollard having a trash can receptacle associated therewith.

FIGS. 25A and 25B are respectively perspective and side elevational views of a second embodiment of a bollard having a trash can receptacle associated therewith.

FIGS. 26A, 26B, and 26C are respectively perspective, front elevational, and side elevational views of a first embodiment of a bollard having an ash urn associated therewith.

FIGS. 27A, 27B, and 27C are respectively perspective, front elevational, and side elevational views of a second embodiment of a bollard having an ash urn associated therewith.

FIGS. 28A, 28B, 28C, 28D, and 28E are respectively perspective, front elevational, left and right side elevational, and top plan views of a grouping of bollards having seating and a matching ash urn and trash can receptacle associated therewith.

FIGS. 29A, 29B, 29C, and 29D are respectively perspective, front elevational, side elevational, and top plan views of a grouping of bollards having seating and signage associated therewith.

FIGS. 30A, 30B, 30C, and 30D are respectively perspective, front elevational, side elevational, and top plan views of a fifth embodiment of a bollard in accordance with the present invention.

FIGS. 31A, 31B, 31C, and 31D are respectively perspective, front elevational, side elevational, and top plan views of a sixth embodiment of a bollard in accordance with the present invention.

FIGS. 32A, 32B, 32C, and 32D are respectively first perspective, second perspective, first side elevational, and second side elevational views of a seventh embodiment of a bollard in accordance with the present invention.

DETAILED DESCRIPTION OF THE PREFERRED EMBODIMENTS

In describing preferred embodiments of the present invention illustrated in the drawings, specific terminology is employed for the sake of clarity. However, the invention is not intended to be limited to the specific terminology so selected, and it is to be understood that each specific element includes all technical equivalents that operate in a similar manner to accomplish a similar purpose.

Referring to FIGS. 1A-1B and 2A-2B, there are shown first and second embodiments 10 and 10' of a bollard that can be used individually or in combination with other similar bollards. The structure of the bollard 10 and 10' is based on the

formation of continuous cross-sections in a series of at least two nested, inverted U-shaped forms (10a and 10b in shown FIGS. 1A and 1B; 10a, 10b, and 10c shown in FIGS. 2A and 2B) set around a common vertical axis A. In order to achieve a nested configuration, the substantially U-shaped forms 10a, 10b, and 10c are of decreasing height. Each substantially U-shaped form has an upper transverse portion 12 and two parallel, vertical legs 14 extending from the upper transverse portion 12. In the embodiments of FIGS. 1A-1B and 2A-2B, the upper transverse portion 12 is curved, with a smooth transition to the legs 14, although other configurations are possible, as discussed below.

Referring to FIG. 3A, an embodiment of a bollard 100 is shown that includes means such as at least one center joining plate for joining the substantially U-shaped forms 10a, 10b, and 10c together as a unit. In this embodiment, the center joining plate is in the form of a disc 20. Preferably, the forms 10a, 10b, and 10c are fastened to the joining means below the upper transverse portions 12 of the forms 10a, 10b, and 10c. Means such as an anchor plate 24 attached to the bottom of the substantially U-shaped forms 10a, 10b, and 10c can also be provided to anchor the substantially U-shaped forms 10a, 10b, and 10c to a support surface. The "footprint" of the assembly is governed by the transverse cross-sections of the substantially U-shaped forms 10a, 10b, and 10c and the number of such forms that are nested.

The forms are not limited to tubing of circular cross-section, but can be made of tubing of other cross-sections including, but not limited to square or rectangular cross-sections. FIGS. 30A-30D and FIGS. 31A-31D show fifth and sixth embodiments 110 and 110', respectively, of a bollard in which the forms 110a, 110b, 110c, and 110d are made of tubing having a square cross section. Each substantially U-shaped form has an upper transverse portion 112 (which in the embodiment of FIGS. 30A-30D and 31A-31D is linear) and two parallel vertical legs 114. In this configuration, the upper transverse portion 112 and the legs 114 can be fit together using miter joints that are welded together to provide a continuous structure. Preferably, the bollards 110 and 110' include joining means such as at least one center joining plate for joining the forms 110a, 110b, 110c, and 110d together as a unit below the upper transverse portion 112. In this embodiment, the center joining plate is in the form of a square 120. Anchoring means are also provided to anchor the substantially U-shaped forms 110a, 110b, 110c, and 110d to a support surface, as discussed hereinafter.

Also, the widths of the forms (that is, the distance between the outside edges of the legs) can either be the same for all forms, which will yield a substantially circular footprint (as shown, for example, FIGS. 3A, 3B, 30A-30D, and 31A-31D), or they can be varied to yield a non-circular footprint. For example, in a bollard comprising four forms set around a common vertical axis to form an angle of 45° between adjacent forms, alternating forms can have widths in a ratio of 1: $\sqrt{2}$, which will yield a square footprint (not shown). Thus, a bollard in which the substantially U-shaped forms are made from tubing with a circular cross-section can have a circular or non-circular footprint; and a bollard in which the substantially U-shaped forms are made from tubing with a square cross-section also can have a circular or non-circular footprint.

For most applications, the forms 10a, 10b, and 10c and 110a, 110b, 110c, and 110d will have a substantially vertical orientation, and where the joining means is a center joining plate, the joining means will have a substantially horizontal orientation. However, it is contemplated that in some applications, the bollard may have a substantially horizontal or

other orientation, and the center joining plate will have a substantially vertical orientation or an orientation otherwise substantially perpendicular to that of the forms 10a, 10b, and 10c and 110a, 110b, 110c, and 110d.

- 5 The center joining plate can be a disc 20 (as shown in FIGS. 3B and 4A), a square 120 (as shown in FIGS. 30A-30D and 31A-31D), a rectangle, or other shape with notches 20b at the perimeter complimentary in shape to the cross-section of the legs 14 or 114 to engage facing surfaces of the legs 14 or 114. 10 The center joining plate can also be a spider 20' or 20" (FIGS. 4B and 4C) having radiating arms 22' or 22", respectively, that engage the facing surfaces of the legs 14 or 114. FIG. 4B shows a first embodiment of a spider 20', in which the sides of the arms 22' are parallel, while FIG. 4C shows a second embodiment of a spider 20", in which the sides of the arms 22" converge. It will be appreciated by those of skill in the art that a center joining plate in the form of a spider, such as the spiders 20' and 20" as shown in FIGS. 4B and 4C can also be adapted to forms made from tubing of non-circular cross-section, such as forms 110a, 110b, 110c, and 110d. It will also be appreciated by those of skill in the art that other configurations of center joining plate can be used.

15 The center joining plate can have a central aperture 20b therein (as shown in FIGS. 3B and 4A-4C), for example to receive a center shaft (as discussed in greater detail below) for enclosing electrical lines and supporting at least one electrically-operated device, such as a lamp, or to receive a center pole for supporting a second fixture above the bollard; although the central aperture 20b can be omitted, as shown and described in connection with the bollard of FIG. 3A.

20 Referring again to FIGS. 3A-3B, and also to FIG. 5 and FIGS. 31A-31D, the anchoring means can be an anchor plate attached to the bottoms of the forms 10a, 10b, and 10c and 110a, 110b, 110c, and 110d, for example by welding. The 25 anchor plate can be a disc 24, as shown in FIGS. 3A-3B and 5, or a square 124, as shown in FIGS. 31A-31D, and is also fastened to a support surface (for example, pavement) by bolts or the like inserted through apertures 24b spaced around the anchor plate 24 or 124 inward of its perimeter. Like the 30 joining means and for the same purpose, the anchor plate can have a central aperture 24a, as shown in FIGS. 3B and 5 in connection with the anchor plate 24. Alternatively, the bottoms of the forms 10a, 10b, and 10c and 110a, 110b, 110c, and 110d can be buried in the ground, preferably anchored in a concrete footing 26, as shown in FIG. 6 and FIGS. 30A-30D. When the forms 10a, 10b, and 10c are anchored in a concrete footing 26, the anchor plate 24 can be omitted.

35 In one embodiment, shown in FIGS. 2A-2B, the bollard has three substantially U-shaped forms 10a, 10b, and 10c of 2 $\frac{3}{4}$ inch O.D. steel pipe, with the substantially U-shaped forms 10a, 10b, and 10c being at an angle of 120° to each other. The footprint formed represents a circle.

40 The size and strength of the material used can have a significant effect on the behavior and strength of the finished bollard. For example, with no change in general appearance, using standard schedule 40 pipe will provide one set of characteristics, while using high-tensile-strength tubular steel of the same outer diameter will yield far different characteristics. Moving the center joining plate up or down, or changing 45 the cross-section of the tubing used to make the forms, or increasing the heights of the substantially U-shaped forms, or changing the configuration of the joining plate, or adding additional joining plates will also have a significant effect on the characteristics of the fixture. Filling the inside of the substantially U-shaped forms with concrete or other filler materials will yield other results. Using multiple bollards of different heights (the height of each bollard being determined

by the height of its tallest substantially U-shaped form) placed adjacent to each other as shown and described in connection with FIGS. 7A-7C will also result in different characteristics, as will joining or linking bollards together using seating sections shown and described in connection with 11A-11C, 12A-12D, 13A-13D, 14A-14D, and 14A-15D, or a sign frame as shown and described in connection with FIGS. 29A-29D, or the canopy of a shelter as shown and described in connection with FIGS. 18A-18C, 19A-19C, and 20A-20B, as functional and structural elements. There are conflicting requirements for strength, rigidity, and ductility that must be addressed.

Assume, for example, that a car is deliberately or accidentally driven toward a facility in which a plurality of the bollards in accordance with the invention are arrayed in front of it. Also assume, for example, that the strength of the anchoring means anchoring the bollards to the ground is sufficient to restrain the fastened portion of each bollard over a known and defined range. Such anchoring means include but are not limited to an anchor plate 24 or 124 held in place by anchor bolts, the extended ends of the legs 14 or 114 held in concrete footings 26, and an in-ground assembly acting as a receiver for the legs 14 or 114 or a joining plate (which would make the bollard removable), etc. Such anchoring means can also include a radially-extending assembly below ground.

When a vehicle strikes the outer circumference of the vertical bollard either used by itself or as part of a larger assembly, it is intended that the bollard will initiate a reaction similar to the concept of the "crumple zone" in automobile design. The energy of the impact will deform the bollard significantly. The horizontal energy of the crash will be deflected in a series of distortions that are both vertical and horizontal, with most of the horizontal energy being deflected in the vertical legs 14. The steel will deform, stretch, and translate energy to the adjacent sections of the substantially U-shaped forms, the joining plates, and any other elements attached to them.

The energy needed to tear, bend, or deform each element of the bollard can be defined by the grade, weight, and characteristics of the material used. In the absorption of energy, the bollard will deform such that enormous energy is absorbed in the translating of the horizontal vector of the collision into the vertical and horizontal distortion of the bollard elements into the bollard cross-section itself. The relationship of the height of the arches, the placement of the joining plates, the number of joining plates, the number of arches, the combination of bollards, etc., all provide enormous flexibility in a homogeneous design motif. Similarly, using other attached elements, including benches, increases the area and function of the "crumple zone" significantly, distributing energy over more space, material, linked bollards, etc.

As discussed above, the joining plates can be in the form of a steel or other disc 20 (FIGS. 3B and 4), a square (FIGS. 30A-30D and 31A-31D) or "spider" framework (FIGS. 4B and 4C) that allows for more or less movement of the individual sections of each substantially U-shaped form. Likewise, changing the height of the inverted substantially U-shaped forms and the number, type, and placement of the joining elements can provide design flexibility in matching sections of the bollard to the intended use.

Examples of applications of the bollard to public-space systems or assemblies are shown and described in connection with FIGS. 7A-7C, 8A-8C, 9A-9C, 10A-10C, 11A-11D, 12A-12D, 13A-13D, 14A-14D, 15A-15D, 16A-16D, 17A-17D, 18A-18C, 19A-19C, 20A-20B, 21A-21B, 22A-22C, 13A-23D, 24A-24B, 25A-25B, 26A-26C, 27A-27C, 28A-28D, and 29A-29D, and include, but are not limited to barri-

ers, seating, lighting, signage, shelters, and litter control. The bollard can be used in a system comprising one or more other bollards and/or site amenities (for example, seating, lighting, signage, shelters, trash can receptacles, and ash urns) that adds security to the usual functions of site amenities. For example, as shown in FIGS. 7A-7C, a plurality of bollards 100 in accordance with the invention can be placed in a grouping 30 for use as a barrier, with a bollard 30a of a first height at the center, and the other bollards 30b of a second, shorter height spaced circumferentially around the first, center bollard 30a. In the embodiment of FIGS. 7A-7C, four bollards 30b are equidistantly spaced around the center bollard 30a. However, it will be appreciated by those of ordinary skill in the art that the number of second, circumferential bollards 30b, as well as their size and spacing, can be varied according to the intended use, available space, and esthetic considerations. It will also be appreciated by those of skill in the art that it is possible to vary the configuration of the bollards used in a grouping 30, for example by changing the number and/or cross-section of substantially U-shaped forms (as shown and described, for example, in connection with FIGS. 30A-30D and FIGS. 31A-31D), by changing the number and configuration or type of the joining means (as shown and described in connection with FIGS. 4A-4C), and by changing the configuration or type of anchoring means.

With minor changes in fastening hardware, one or more bollards can be used as supports for installing seating, lighting, signage, shelters, etc., with secure and protected electrical connections (where needed), flexible spacing, etc. For example, seating can be installed around a single bollard 100 (FIGS. 8A-8C, 9A-9C, and 10A-10C) or around a grouping of two or more bollards 100 (FIGS. 11A-11D, 12A-12D, 13A-13D, 14A-14D, 15A-15D, 16A-16D, and 17A-17D); lamps can be installed within or above a bollard 100 (FIGS. 21A-21B); signage can be supported by a single bollard 100 or between a pair of bollards 100 (FIGS. 29A-29D); a shelter can be supported by two or more bollards 100 (FIGS. 18A-18C, 19A-19C, and 20A-20B); and trash can receptacles and/or ash urns can be supported by a single bollard 100 (FIGS. 22A-22C, 23A-23D, 24A-24B, 25A-25B, 26A-26C, and 27A-27C) or between a pair of bollards (not shown) or on separate bollards 100 in a system of at least one bollard and at least one site amenity (FIGS. 28A-28D). In some embodiments the at least one site amenity will function to join or link together at least two bollards 100 to provide a public-space system having different behavior and strength characteristics than a single bollard 100.

It will also be appreciated by those of skill in the art that it is possible to vary the configuration of the bollard combined with the site amenities, for example by changing the number and/or cross-section of substantially U-shaped forms (as shown and described, for example, in connection with FIGS. 30A-30D and FIGS. 31A-31D), by changing the number and configuration or type of the joining means (as shown and described in connection with FIGS. 4A-4C), and by changing the configuration or type of anchoring means.

Referring to FIGS. 8A-8C, 9A-9C, and 10A-10C, there are shown three embodiments in which a single bollard 100 has seating fixtures in the form of fan-shaped benches 40 associated therewith. In the embodiment shown in FIGS. 8A-8C, the fan-shaped benches 40 are installed around the bollard 100, supported by pedestals 42 set into a support surface radially outwardly from the bollard 100. In the embodiments shown in FIGS. 9A-9C and 10A-10C, the fan-shaped benches 40 are attached to the bollard 100 by different styles of brackets 44 and 44'. It will be appreciated by those of skill in the art that either multiple seating fixtures or a single, continuous

seating fixture can be associated with the bollard 100, that the seating fixture can be solid, slatted, latticed, and other styles; and that the style of brackets and pedestals used to support the seating fixtures are not limited to those illustrated, but can be selected from any other style suitable to the intended use.

Referring to FIGS. 11A-11D, 12A-12D, 13A-13D, 14A-14D, 15A-15D, 16A-16D, and 17A-17D, there are shown seven embodiments in which groupings of at least two bollards 100 have at least one seating fixture associated therewith. FIGS. 11A-11D, 12A-12D, and 13A-13D show embodiments in which the bollards 100 are arranged in a line. In the embodiment shown in FIGS. 11A-11D, two bollards 100 are spaced apart, and brackets 44 attached to the universal public-space figures support an elliptical bench 50, the vertical axes of the bollards 100 being positioned approximately at the foci of the ellipse. The embodiment of FIGS. 12A-12D is similar to the embodiment of FIGS. 11A-11D, except that three, rather than two bollards 100 are provided. The embodiment of FIGS. 13A-13D is similar to the embodiment of FIGS. 11A-11D, except that the curved portions of the bench 50 and their supporting brackets 44 are omitted, so that the seating fixture comprises two separate rectangular benches 52, between which the two bollards 100 are sandwiched.

FIGS. 14A-14D, 15A-15D show embodiments in which three bollards 100 are arranged in a triangle. In the embodiment shown in FIGS. 14A-14D, brackets 44 attached to the bollards 100 support a separate rectangular bench 52 on each side of the triangle. In FIGS. 15A-15D, brackets 44 attached to the bollards 100 support a triangular bench 54 around the bollards 100.

In FIGS. 16A-16D, four fan-shaped benches 40 are associated (by attachment with brackets 44) with the exterior bollards 100 in a grouping 30 of five bollards 100 arranged as described in connection with FIGS. 7A-7C. The embodiment of FIGS. 17A-17D is similar to the embodiment of FIGS. 16A-16D, except that the bollards 100 are more closely spaced to each other.

It will be appreciated by those of skill in the art that the configuration of the seating fixtures and their supports can be varied in any manner suitable to their intended use, and taking into account esthetic considerations. For example, a pair of bollards 100 can be surrounded by an elliptical bench 50, as in the embodiment of FIGS. 11A-11D, sandwiched between a pair of rectangular benches 52, as in the embodiment of FIGS. 13A-13D, or can even be associated with a single bench 52 between them; and more than two bollards 100 can be arranged in a line between the seating fixtures, as shown in FIGS. 12A-12D. The embodiments of FIGS. 14A-14D and FIGS. 15A-15D can be modified for use with more than three bollards 100, with the bollards 100 being positioned at the vertices of a polygon, and the seating fixture or fixtures being configured accordingly, with a separate seating fixture (for example, a rectangular bench 52) on each side of the polygon or a polygonal bench extending around the bollards 100. Similarly, the embodiments of FIGS. 16A-16D and 17A-17D can be modified for use with two, three, or more than four bollards 100, with the shape of the fan-shaped benches 40 being adjusted in accordance with the spacing of the bollards 100; and can also be modified by adjusting the spacing between the bollards 100, as shown in FIGS. 17A-17D. Also, the seating fixtures can be attached to the universal public space fixtures 100 by brackets of any suitable configuration, such as brackets 44 or 44' as shown in FIGS. 9A-9C, 10A-10C, 11A-11D, 12A-12D, 13A-13D, 14A-14D, and 15A-15D; or can be supported on pedestals, such as pedestals 42 as shown in FIGS. 8A-8C, in close proximity to the universal public space fixtures 100.

It will also be appreciated by those of skill in the art that it is possible to vary the configuration of the bollard combined with the various seating fixtures and their supports, for

example by changing the number and/or cross-section of substantially U-shaped forms (as shown and described, for example, in connection with FIGS. 30A-30D and FIGS. 31A-31D), by changing the number and configuration or type of the joining means (as shown and described in connection with FIGS. 4A-4C), and by changing the configuration or type of anchoring means.

Referring to FIGS. 18A-18C, 19A-19C, and 20A-20C, there are shown three embodiments 60, 60', and 60" of shelters in which a canopy is supported by multiple bollards. In the embodiment of FIGS. 18A-18B, the shelter 60 comprises a pair of bollards 100, a canopy 62 above and spaced from the bollards 100, and a pair of brackets 64 extending outwardly from opposite sides of the upper transverse portion 12 of on one of the forms 10a, 10b, and 10c, in this case shortest of the forms, 10c. Alternatively, the canopy 62 can be supported by center poles 64' extending through and above a pair of spaced bollards 100', as shown in FIGS. 19A-19C. The center poles 64' extend through the bollards 100' to the bottom of the substantially U-shaped forms 10a, 10b, and 10c, and the center joining plates 20 of the bollards 100' have a central aperture 20a therein, for receiving the center poles 64'. In the embodiment of FIGS. 20A-20B, the shelter 60" comprises a canopy 62" supported by four center poles 64' arranged in a rectangle and extending from four correspondingly arranged bollards 1000. Each of the bollards 1000 has two center joining plates 20, spaced vertically along the vertical axis of the bollards 1000.

It will be appreciated by those of skill in the art that the shape and size of the canopy can be varied according to the intended use and esthetic considerations. Such variations include, but are not limited to, a shape that is elliptical in outline, as shown in FIGS. 18A-18C and 19A-19C, a shape that is peaked, as also shown in FIGS. 18A-18C and 19A-19C, a shape that is rectangular in outline, as shown in FIGS. 20A-20B, and a shape that is bowed, as also shown in FIGS. 20A-20B. Similarly, the number of bollards used to support the canopy can be varied, for example by arranging at least two in spaced linear fashion, as shown in FIGS. 18A-18C and 19A-19C, or by using multiple pairs as shown in FIGS. 20A-20B. As will be appreciated by those of skill in the art, the length of the shelter can be increased by increasing the number of bollards used to support the canopy. As also will be appreciated by those of skill in the art, the shelter can also include other site amenities, such as one or more fan-shaped benches 40 associated with each bollard 100 or 100', or at least one rectangular bench 52 or elliptical bench 50 associated with pairs of the universal public-spaced fixtures 100 or 100'.

Referring to FIGS. 21A and 21B, there is shown a bollard 100' having a lamp 70 installed therein. In this embodiment, both the center joining plate 20 and the anchor plate 24 have apertures 20a therethrough to accommodate a center shaft 72 for enclosing electrical lines (not shown) and supporting the lamp 70, and the shaft 72 terminates just above the center joining plate 20 so that the lamp 70 supported thereby is fully enclosed by the upper end of the bollard 100'. It will be appreciated by those of skill in the art that the shaft 72 can be extended above the bollard 100' so that the lamp 70 is above it, rather than enclosed by it.

Referring to FIGS. 22A-22B and 23A-23B, there are shown two embodiments of an ash urn 80a and matching trash can receptacle 80b, associated with a bollard 100. In the embodiment of FIGS. 22A-22B, the brackets 82 are attached at one end between adjacent legs 14 of two substantially U-shaped forms and at the other end to the sides of the ash urn 80a and trash can receptacle 80b. In the embodiment of FIGS. 23A-23B, a single bracket 82' is provided, attached at its center portion to the top of the anchor plate 24 and at the ends to the bottoms of the ash urn 80a and the trash can receptacle

11

80b. It will be appreciated by those of skill in the art that the ash urn **80a** and trash can receptacle **80b** can have a variety of configurations (examples of different configurations include, but are not limited to the designs of U.S. Pat. Nos. D304,253, D304,632, D314,461, D322,347, D322,348, D322,702, D353,250, D417,053, D441,932, D445,982, D450,166, D452,760, D454,238, D458,431, D460,591, D460,592, D460,593, D461,939, which are incorporated herein by reference in their entireties), they can be attached to the bollard **100** relative to different pairs of legs **14**, and they can be associated singly with the bollard **100**, as shown in FIGS. 24A-24B, 25A-25B, 26A-26C, and 27A-27C, rather than together (that is, an ash urn **80a** alone can be associated with the bollard **100**, as shown in FIGS. 26A-26C and FIGS. 27A-27C, as can the trash can receptacle **80b**, as shown in FIGS. 24A-24B and 26A-26B).

It is contemplated that the bollard **10**, **10'**, **100**, **100'**, and **1000** in accordance with the present invention can be combined with multiple types of public space fixtures, to provide a multi-function public-space system. For example, two or more bollards fixture **10**, **10'**, **100**, **100'**, and **1000** can be used to support both seating and litter control fixtures, such as the benches **40** and **52** and ash urn **80a** and trash can receptacle **80b** as shown in FIGS. 28A-28D; and two or more spaced bollards **10**, **10'**, **100**, **100'**, and **1000** can be used to support both seating and signage fixtures, such as the bench **50** and sign **90** as shown in the embodiment of FIGS. 29A-29D, which are respectively attached to the bollards **100** by brackets **44** and brackets **92**.

As can be appreciated from the foregoing, the esthetic requirement for public-space fixtures is well-served by the bollard in accordance with the invention, as opposed to conventional concrete or other protective fixtures. The system of the bollard and associated site amenities is also extremely cost effective in that for little more than the cost of the amenities themselves, the added element of security can be addressed. The bollard alone or the system can be installed with relatively common and available materials and equipment at relatively low cost.

Modifications and variations of the above-described embodiments of the present invention are possible, as appreciated by those skilled in the art in light of the above teachings. For example, as shown in FIGS. 32A-32D with respect to a seventh embodiment **110"** of a universal public-space fixture, the upper transverse portion **12"** of the substantially U-shaped forms can be asymmetrically inclined, rather than symmetric about the axis A. It is therefore to be understood that, within the scope of the appended claims and their equivalents, the invention may be practiced otherwise than as specifically described.

What is claimed is:

1. A bollard comprising at least two nested, inverted, substantially U-shaped forms of decreasing height set around a common vertical axis in different intersecting planes, the U-shaped forms being made of metal pipes, wherein each substantially U-shaped form has an upper transverse portion and two parallel, vertical legs extending from the upper transverse portion, and wherein the U-shaped forms have physical characteristics such that on impact by a moving vehicle, including an automobile or a truck, the U-shaped forms will initiate a "crumple zone" type reaction, so as to provide barrier protection against threats posed by vehicular traffic.

2. The bollard of claim **1**, further comprising means for joining the substantially U-shaped forms together as a unit.

3. The bollard of claim **1**, further comprising means for anchoring the forms to a support surface.

12

4. The bollard of claim **1**, comprising three substantially U-shaped forms.

5. A barrier comprising a plurality of bollards as claimed in claim **1** arranged in a grouping.

6. The barrier of claim **5**, comprising a first, center bollard and a plurality of circumferential bollards surrounding the center bollard.

7. A bollard comprising at least two nested, inverted, substantially U-shaped forms of decreasing height set around a common vertical axis in different intersecting planes, the U-shaped forms being made of metal pipes, and wherein the U-shaped forms further have physical characteristics such that the energy of the impact will deform the bollard significantly, with the horizontal energy of the impact being deflected in a series of distortions that are both vertical and horizontal, with most of the horizontal energy being deflected in the vertical legs, so as to provide barrier protection against threats posed by vehicular traffic.

8. The bollard of claim **7**, further comprising means for joining the substantially U-shaped forms together as a unit.

9. The bollard of claim **7**, further comprising means for anchoring the forms to a support surface.

10. The bollard of claim **7**, comprising three substantially U-shaped forms.

11. The bollard of claim **1**, wherein each substantially U-shaped form has an upper transverse portion and two parallel, vertical legs extending from the upper transverse portion.

12. A barrier comprising a plurality of bollards as claimed in claim **10** arranged in a grouping.

13. The barrier of claim **11**, comprising a first, center bollard and a plurality of circumferential bollards surrounding the center bollard.

14. A bollard comprising at least two nested, inverted, substantially U-shaped forms of decreasing height set around a common vertical axis in different intersecting planes, the U-shaped forms being made of metal pipes, wherein:

each substantially U-shaped form has an upper transverse portion and two parallel, vertical legs extending from the upper transverse portion, and

the U-shaped forms have physical characteristics such that:

(a) on impact by a moving vehicle, including an automobile or a truck, the U-shaped forms will initiate a "crumple zone" type reaction, and

(b) the energy of the impact will deform the bollard significantly, with the horizontal energy of the impact being deflected in a series of distortions that are both vertical and horizontal, with most of the horizontal energy being deflected in the vertical legs,

so as to provide barrier protection against threats posed by vehicular traffic.

15. The bollard of claim **14**, further comprising means for joining the substantially U-shaped forms together as a unit.

16. The bollard of claim **14**, further comprising means for anchoring the forms to a support surface.

17. The bollard of claim **14**, comprising three substantially U-shaped forms.

18. A barrier comprising a plurality of bollards as claimed in claim **14** arranged in a grouping.

19. The barrier of claim **18**, comprising a first, center bollard and a plurality of circumferential bollards surrounding the center bollard.
